COMBINED SCREEN AND STORM SASH.

1,426,267.

Specification of Letters Patent. Patented Aug. 15, 1922.

Application filed April 30, 1920. Serial No. 377,874.

To all whom it may concern:

Be it known that I, LAWRENCE W. FISHER, a citizen of the United States, residing at Wilsonville, in the county of Furnas and State of Nebraska, have invented certain new and useful Improvements in Combined Screen and Storm Sashes; and I do hereby declare the following to be a full, clear, and exact description of the invention, such 10 as will enable others skilled in the art to which it appertains to make and use the same.

This invention relates to combined screen and storm window sashes and it consists in 15 the novel features hereinafter described and claimed.

An object of the invention is to provide a sash of simple and durable structure adapted to be applied to a window frame and 20 which may be easily and quickly transformed from a storm sash structure to a screen sash structure and vice versa.

With this object in view the sash frame comprises top, bottom side and mullion rails 25 which are provided at their inner edges with recesses having angularly disposed side walls and adapted to receive sashes which are provided at their inner edges with recesses having angularly disposed side walls. The 30 recesses of the pieces of the sash are adapted to receive the edge portions of a screen or sheet of glass and beading strips are applied to the outer surfaces of the sash pieces and extend over the edge portions of the 35 sheet of glass or screen whereby they are held in position in the sashes.

In the accompanying drawing,

Figure 1 is a side elevation of the combined screen and storm sash with glass 40 panes mounted therein.

Figure 2 is a longitudinal sectional view of the same cut on the line 2—2 of Figure 1 but showing screen instead of glass.

Figure 3 is a fragmentary sectional view 45 cut on the line 3—3 of Figure 1 but showing screen instead of glass.

The rails 1 of the sash frame and the mullion rail 1' thereof are provided with recesses the full length of the rails and which 50 are provided with angularly disposed side walls. These recesses are located at the corner portions of the rails and consequently the recesses open at the outer side of the

sash and at the inner edges of the rails. A sash 3 is located in the recesses 2 and in 55 contact with the inner walls thereof. The sash 3 may be secured in position in the rails 1 and 1' by means of nails, brads or other suitable securing devices and in a usual manner. The side pieces of the sash 3 are 60 provided at their inner portions with recesses 5 which extend the full length of the pieces and the recesses 5 are provided with angularly disposed side walls. The recesses 5 are located at the corner portions of the 65 side pieces of the sash and consequently the recesses open outwardly at the outer side of the sash and open inwardly at the inner sides of the sash pieces. The recesses 5 are adapted to receive the edge portions of a 70 sheet of glass 6 or a screen 6' and securing beads 7 are secured to the outer surface of the sash 3 and the inner edge portions of the beads 7 overlap the edge portions of the sheet 6 or screen 6' when they are held in 75 position in the recesses 5.

From the foregoing description taken in conjunction with the accompanying drawing, it will be seen that a combined screen and storm sash of simple and durable structure is provided and that the same may be 80 easily and quickly transformed from a screen sash to a storm sash structure and vice versa.

Having thus described the invention what 85 is claimed is:—

A device of the class described having a frame and sashes, said frame having recesses to receive said sashes between its side faces with one side face of the frame flush with 90 one side face of each of the sashes, a mullion between the recesses, said sashes and said recesses being substantially of the same size, said frame having a retaining portion to overlap the other side of each face of the 95 sashes, the sashes at the first mentioned side face being rabbeted to selectively receive either screens or glass plates, and means to secure either said screens or glass plates in the rabbets.

In testimony whereof I affix my signature in presence of two witnesses.

LAWRENCE W. FISHER.
